Des. 207,052
Patented Feb. 28, 1967

207,052

AIR-DRIVEN AUTOMOBILE

Paul M. Lewis, P.O. Box 652, Golden, Colo. 80401

Filed May 2, 1966, Ser. No. 2,106

Term of patent 14 years

(Cl. D14—3)

FIG. 1 is a top plan view of an air-driven automobile showing my new design;

FIG. 2 is a front, elevational view thereof; and

FIG. 3 is a side elevational view thereof, the side opposite being similar in appearance.

I claim:

The ornamental design for an air-driven automobile, as shown and described.
